Des. 184,726
Patented Mar. 31, 1959

184,726

JAR AND BOTTLE OPENER

Walter L. Gill, Redlands, Calif.

Application January 27, 1958, Serial No. 49,412

Term of patent 14 years

(Cl. D44—29)

Fig. 1.

Fig. 2.

Fig. 3.

Fig. 1 is a side view of a jar and bottle opener showing my new design;

Fig. 2 is an inside face view, and

Fig. 3 is a transverse sectional view on line 3—3 of Fig. 2.

I claim:

The ornamental design for a jar and bottle opener, as shown and described.
